UNITED STATES PATENT OFFICE.

WILLIAM G. CLOPTON, OF BALTIMORE, MARYLAND, ASSIGNOR OF ONE-HALF TO JACOB C. MOSER, OF BALTIMORE, MARYLAND.

LOW-CUT SHOE.

No. 876,897.

Specification of Letters Patent.

Patented Jan. 14, 1908.

Application filed September 20, 1907. Serial No. 393,754.

To all whom it may concern:

Be it known that I, WILLIAM G. CLOPTON, a citizen of the United States, residing at Baltimore, in the State of Maryland, have 5 invented certain new and useful Improvements in Low-Cut Shoes, of which the following is a specification.

This invention relates to improvements in low-cut shoes and slippers and has particular 10 reference to an improved device within the shoe or slipper for retaining the same on the foot of the wearer.

It is desirable in the manufacture of low-cut shoes and slippers worn by women, to 15 have them cut low and in the efforts of the manufacturer to secure the effects desired, the limit has been in many instances over-reached, because of the inability to retain the shoes on the feet. The result is that 20 such low-cut slippers ride up and down on the heel and wear the stocking, as the result of the friction thus produced; they spread on the sides when the weight is placed on the toes and thus draw the heel portion of the 25 slipper from the foot, and in many instances in walking down stairs, the heels by being released because of the spreading of the sides when the weight is placed on the toes, have caused the wearer to fall.

30 One object of the invention is to provide a device that shall be entirely concealed from view when in use; give ease and comfort to the foot, and which may coact between the slipper and the foot in such manner 35 as to cause the slipper to hug closely to the foot during such movements of the foot as ordinarily tend to dislodge the slipper or shoe.

Another object is to provide an improved 40 device that will draw the heel or counter of the slipper against the heel of the wearer at such times when the sides tend to spread and by drawing the counter up close against the heel of the foot, produce a tension on the 45 sides and at the instep which will cause the shoe to fit snugly around and closely follow the contour of the foot, thus avoiding friction between the foot and slipper and prevent undue wearing on the stocking.

50 I am aware that it has heretofore been proposed to provide an elastic band at the inside rear portion of a shoe to exert its tension against the back of the ankle but said strip only extends crosswise at the counter

and the two ends of such strip are secured to 55 the counter.

I am also aware that it has been proposed to provide straps that extend from the heel of an overshoe forward and over the instep of the inclosed shoe but in none of the devices within my knowledge are the low shoes provided on the interior with devices that have a construction or an operation like that herein disclosed by me.

The invention is illustrated in the accompanying drawing, in which,—

Figure 1, shows a perspective view of a slipper provided with an improved construction of retaining device. Fig. 2, illustrates a plan view of the same. Fig. 3, 70 shows a central longitudinal sectional view through the same. Fig. 4, illustrates a detail of the device employed to secure the ends of the elastic band in the slipper, and Fig. 5, shows a portion of the slipper lining 75 at the point where the band is sustained thereby.

Referring to the drawing the numeral, 1, designates the slipper having the usual opening, 2, at the upper side thereof for the insertion of the foot.

At the rear and on the inside of the slipper I provide loops, 3, preferably at diametrically opposite sides of the counter portion, 4, of the slipper. In the present instance these 85 loops, 3, are formed by making parallel and substantially vertical incisions or slits, 5, in the lining, 6, thus forming the loop, 3, from the lining material that remains between the slits or incisions.

Above the shank or waist portion, 7, and also on the interior of the slipper I provide loops, 8, at opposite sides and also in the lining by again slitting the latter.

At the forward portion of the slipper and beneath the instep, 9, I preferably form parallel spaced-apart horizontal slits or incisions, 10. Thus it will be seen that preferably I provide three sets of slits in the lining below the upper edge, 11, of the slipper and at 100 spaced-apart intervals therein.

A band or strip, 12, of any suitable material, and it may be of elastic if desired is provided at its ends with some suitable device for permitting its attachment to the interior of the shoe beneath or on the instep. In the present instance the ends of this band are provided with a flat flexible metal plate,

13, having a curved end portion, 14, with a flange, 15, beneath which the end of the band is passed and clenched while said plate is also provided with oppositely-projecting 5 prongs, 16. I may, for the purpose of securing a better connection between the band and plate, provide stitches or other fastening devices, 17, which extend over the prongs 16.

In attaching the band or strip to the slipper I first bend the prongs, 16, at one end so they will enter the horizontal slits, 10, in the lining adjacent the instep. I then feed the free end of the band or strap freely through the loop, 8, above the shank or waist then 10 through the loop, 3, at the counter, 4. The band is then extended across the inside of the slipper to and freely through the loop, 3, at the opposite side of the counter then forward through the loop, 8, and finally the 15 end is secured to the lining adjacent the instep. It will thus be seen that the band or strip extends along one side of the slipper then across to the opposite side forming a yielding heel-engaging stretch, 18, and then 20 forward along said opposite side.

As the two ends of the band or strip are secured forward any strain toward the rear against the heel-engaging stretch, 18, will cause an inward pull on the opposite sides adjacent the shank as the tendency of such pull will be to straighten the band out while the same pull tends to draw the forward portion of the slipper back over the instep of the foot. The effect of strains at either end of the opening 30 is to contract the opening by straightening the band stretches along the opposite sides and in the effort to straighten out the entire opening, 2, of the slipper is contracted about the foot and at such times the slipper is more 35 securely held about the foot.

It will be understood that the band extends along the opposite inner sides of the shoe and forms a loop at the heel end thereof, and that the area of the opening within the 40 side and end stretches of the band is less than the area of the shoe opening so that when the foot is inserted in the shoe opening 45

the end stretch, 18, of the band must yield rearwardly and in doing so the side stretches draw the sides of the shoe in close against the 50 foot.

Having thus described my invention what I claim is,—

1. A shoe having a band on its inside below the surrounding edges of the opening,— 55 said band being spaced from the heel end of the shoe and extending in a direct line cross-wise of the opening adjacent the counter and being loosely sustained at opposite sides of the shoe and extending forwardly from the 60 counter.

2. A shoe having a band on its inside below the edges of the opening which extend rearwardly along the opposite longitudinal sides of the shoe and said band also extending from one side of the counter to the other and adjacent but spaced from the rear of the shoe and said band being loosely sustained at the sides of said counter. 65

3. A shoe having a band on its inside below the edges of the opening, said band extending continuously along one inner side of the shoe and crossing over to the opposite inner side adjacent the counter but spaced from the end of the shoe and then extending 75 along said opposite inner side of the shoe and means for sustaining said band loosely between its ends. 70

4. A shoe having a band wholly on the inside thereof extending along the opposite 80 inner side surfaces and across at the heel but spaced from the end of the shoe, and said band being sustained by said inner side surfaces and forming an opening inside of the shoe of less area than the shoe opening 85 whereby to draw the side of the shoe in against the foot when the latter is inserted in the shoe.

In witness whereof I affix my signature in presence of two witnesses.

WILLIAM G. CLOPTON.
